GUARD PLATE FASTENER

Filed May 12, 1932

H. P. CHRISTENSEN, INVENTOR

BY *David O. Barnell*

ATTORNEY

UNITED STATES PATENT OFFICE

HANS P. CHRISTENSEN, OF DAVEY, NEBRASKA

GUARD-PLATE FASTENER

Application filed May 12, 1932. Serial No. 610,843.

My invention relates to reciprocating cutters for harvesting machines, and particularly to guard-fingers and ledger-plates for use on such cutters. It is the object of my invention to provide, for use in mowers and other harvesting machines which employ reciprocating cutters, means for fastening the ledger-plates to the guard-fingers, whereby the removal and replacement of said plates may be greatly facilitated, and the replacement of the guard-plates effected without removing the guards from the finger-bar, or removing the latter from the machine, and whereby such replacements or repairs may be made in the field and with a minimum of delay and loss of time in the use of the machine.

In the accompanying drawing Fig. 1 is a longitudinal vertical section through a guard-finger having a ledger-plate secured thereon by means embodying my invention, Fig. 2 is a horizontal section of the same on the line 2—2 of Fig. 1, Fig. 3 is a transverse section on the lines 3—3 of Figs. 1 and 2, and Fig. 4 is a detail perspective view of the connector-plate alone.

My invention is adapted for use on reciprocating cutters of the ordinary or standard construction, wherein a finger-bar 10 has a plurality of guard-fingers 11 affixed thereon in uniformly spaced longitudinal relation, and extending forwardly therefrom; there being a reciprocating sickle-bar 12 extending parallel with the finger-bar adjoining the front edge thereof and carrying cutter-plates 13 which rest upon the upper faces of the ledger-plates 14 carried upon the guard-fingers within the notched or forked forwardly extending portions thereof. Each ledger-plate 14 has in the rear end thereof a semi-circular notch adapted to fit over a similarly shaped lug 15, and at the front end is shouldered to form a lug 16 adapted to fit within a recess in the guard. Adjacent to the notched rear end of the ledger-plate is a countersunk opening for receiving a rivet 17 by which the plate is prevented from being displaced vertically. It is to be understood that the ledger-plate 14, the sickle-members 12 and 13, and the finger-bar 10, as represented in the drawing, are all of the usual or standard construction, and that the guard-finger 11 is also of the usual standard formation except as hereinafter noted. In the ordinary structure, the lug 15, which fits in the notched rear end of the ledger-plate, is formed integrally with the guard-finger, and the rivet 17 is extended down through an opening therefor in the lower portion of the guard, so that to remove the plate from the guard it is necessary to cut a head from the rivet and drive or drill the body of the rivet out of the openings therefor in the plate and guard; and in securing the plate upon the guard a rivet must be inserted and headed. In my improved structure, however, the semi-circular lug 15 is formed on a separate piece or connector 18 which extends forward beneath the plate, past the opening for the rivet 17, and has an opening therein for receiving the rivet. The longitudinal edges of the connector 18 are beveled to a dovetail formation, and in the guard beneath the rear portion of the plate 14 there is formed a dovetail recess or socket adapted to receive said dovetailed edges of the connector. In the rear portion of the connector, and extending through the lug 15, is an opening 19 adapted to register with an opening 20 in the lower portion of the guard when the connector is seated in the dovetail socket therefor, so that a pin 21 may be inserted in said registering openings to prevent rearward displacement of the connector.

In the use of my invention, a connector of the described character is provided for each ledger-plate that is to be used, and said parts are assembled and permanently secured together by suitable means such as the rivet 17. By sliding the ledger-plate and connector assembly into the guard-finger from the rear, the rounded front portion of the connector readily enters the dovetail socket therefor in the guard, and the connector becomes firmly seated in said socket simultaneously with the seating of the lug 16 on the front end of the plate within the recess therefor in the front portion of the guard. Upward and lateral displacement of the ledger-plate are effectively prevented when the connector is seated in the guard.

5 nector and the lug 16 are fully seated respectively in the socket and recess, and rearward displacement is prevented by inserting the pin 21 in the registering holes 19 and 20 of the connector and guard. Said pin 21 may be of wood and of a diameter requiring the same to be driven into the holes, so as to remain therein at the position to which it is driven. When it is desired to remove the plate from 10 the guard, it is merely necessary to drive the pin 21 out of the holes 19 and 20, after which the plate and connector are moved rearwardly to displace the connector from the dovetail socket and simultaneously displace the lug 16 from the recess therefor in the front portion of the guard. It is noted that the length of the connector 18 is not greater than the width of the sickle-bar 12, and its depth or thickness is substantially the same 15 as that of the sickle-bar, so that when withdrawing the connector from its socket, or when disposing the same in position for insertion in the socket, the connector will lie in the space between the rear end of the 20 socket and the front edge of the finger-bar 10.

25 From the foregoing description it will be apparent that my invention provides means by which the ledger-plates may be very easily and quickly removed and replaced upon the guards. The user of a harvesting machine 30 may carry thereon a supply of the ledger-plates, equipped with the connectors, and at any time that a change is required an old ledger-plate may be removed by merely driving out the pin 21 which retains the same in 35 place, and a new plate inserted and secured in place by driving a wooden pin into the registering holes in the connector and guard. The cost of manufacture of the guard-fingers, 40 with the dovetail sockets therein for the connectors, need be but little if any greater than for guard-fingers of the usual or standard form; standard ledger-plates are used; and the connectors may be produced very cheaply 45 by drop-forging; so that the cost of the improved equipment is only nominally greater than for the ordinary structure.

50 Now, having described by invention, what I claim and desire to secure by Letters Patent is:

55 1. In a structure of the class described, the combination with a guard-finger and a ledger-plate, of means forming a socket in said guard-finger, a connector affixed beneath the ledger-plate and slidably longitudinally into and from said socket in the guard-finger, the 60 guard-finger and said connector having vertical openings registering when the connector is seated in said socket, and a pin insertible in said registering openings to hold the connector in seated position in the socket.

65 2. In a structure of the class described, the combination with a ledger-plate, and a guard-finger recessed to receive the forward end of the ledger-plate and provided

70 with a socket extending longitudinally beneath the rear portion of the ledger-plate, of a connector-plate fitting slidably in said socket, means for affixing said ledger-plate to said connector-plate, and removable means for holding said connector-plate in fixed longitudinal relation to said socket.

75 3. In a structure of the class described, the combination with a ledger-plate, and a guard-finger recessed to receive slidably the front portion of the ledger-plate and provided with a longitudinally extending dovetail socket beneath the rear portion of the ledger-plate, 80 of a connector having a plate portion insertible slidably in said dovetail socket from the rear end thereof only, means for affixing the ledger-plate to said connector, said connector and guard-finger having registering openings 85 therein and a removable pin insertible in said registering openings to retain the connector in said socket.
